Des. 489

John S. Perry of Albany, N.Y.
Assignor to
Fagger, Breadwell & Perry of same place
Letters Patent No 489, Dated Aug 17th 1853

The schedule referred to in these Letters Patent and making part of the same

Be it known that I John S. Perry of the City of Albany State of New York, have produced an ornamental design for a Cooking Stove (which stove I have named the Black Diamond,) and I do hereby declare that the annexed drawings are accurate & full delineations of the ornamental parts with their several ornaments; the side plate with doors, not represented being symmetrically similar to that represented, and where portions of the sections of the plates only are shewn, the portions not shewn being similar to & symmetrical with those shewn.

What I claim as my production & desire to secure by Letters Patent, is the combination and arrangement of ornamental figures and forms represented in the accompanying drawings, forming together an ornamental design for a Cooking Stove.
